UNITED STATES PATENT OFFICE.

GERMAN L. BAXTER, OF LEXINGTON, KENTUCKY.

RAIL-JOINT.

SPECIFICATION forming part of Letters Patent No. 632,625, dated September 5, 1899.

Application filed October 22, 1898. Serial No. 694,256. (No model.)

To all whom it may concern:

Be it known that I, GERMAN L. BAXTER, of Lexington, in the county of Fayette and State of Kentucky, have invented a new and Improved Rail-Joint, of which the following is a full, clear, and exact description.

My invention relates to an improvement in rail-joints of the suspension kind and is provided with a cross-bar which engages the under sides of the rails.

My invention comprises the novel features hereinafter described and claimed.

Reference is to be had to the accompanying drawings, forming a part of this specification, in which similar characters of reference indicate corresponding parts in all the figures.

Figure 1 is a side elevation of my improved rail-joint. Fig. 2 is a plan of the same. Fig. 3 is a cross-section taken upon the line 3 3 of Fig. 2. Fig. 4 is a side elevation of a modified form of construction. Fig. 5 is a plan view of the same, and Fig. 6 is a cross-section taken upon the line 6 6 of Fig. 5.

The object of my invention is to support the joint at the ends of the rails and to bind the rails together in such manner that the joint cannot well drop down, but will be maintained at the same level as the central portion of the rail and will thus prevent the shock due to dropping of the joints.

My rail-joint consists of two principal members which are secured upon each side of the rail A and are connected by a third member. The members which are connected to the side of the rails consist, first, of a fish-plate member B, which engages the side of the rail and lies between the head and the base of the rail. Connected to each end of the fish-plate member is the suspension member C, which consists of a bar either welded to the fish-plate member or secured firmly thereto by other means, the central portion passing outside of the bases of the rail and dropping beneath the same, so as to permit the passage of a key D between the upper side of the suspension member and the base of the rail.

The members B and C are duplicated on each side of the rail, and the key D rests with

one end upon each suspension member, and 50 said members are so proportioned that the key D will press firmly against the under side of the rail and hold the same up and prevent its dropping. The two fish-plate members B are preferably secured to the rails A by 55 means of rivets E, which are inserted while hot, and thus secure the members B and C and the rail A firmly together. The key D has a downwardly-projecting rib d at each end, which prevents the withdrawal of the key 60 from its position upon the suspension members and beneath the rail.

In Figs. 4, 5, and 6 a modified form of construction is shown, in which the fish-plate member and the suspension member upon 65 each side form integral parts of one plate. This plate is bent so that one portion B' forms the fish-plate and lies between the head and base of the rail, a central portion F rests upon the base of the rail, and the opposite 70 portion C' extends downward outside the rail-base and forms the suspension member, being provided with a slot G for the reception of the key D.

The key D is similar in construction to that 75 previously described, excepting that in cases where the joint is used in connection with electric railways a plate H of copper or similar material is placed upon the key and beneath the base of the rail, overlapping the 80 joint between two rails, and thus forming an efficient electrical joint. In order to secure this plate in place and prevent its removal, the upper surface of the key is slightly recessed, the walls of said recess stopping 85 short of the sides of the key, thus holding the plate H in place.

A rail-joint of the character described will be cheap in construction and may be made of such strength that the rail is as stiff and 90 strong at the joint as at any other place and will thus help to maintain a perfectly level grade.

Having thus fully described my invention, I claim as new and desire to secure by Letters 95 Patent—

A rail-joint, comprising two parts each consisting of a bar member adapted to lie between

the base and head of the rail, and a suspension member having its ends engaging the ends of the bar member and with its center dropping below and outside of the rail-base, 5 rivets passing through the bar and suspension members and the rail securing them rigidly together, and a key entering between the

central parts of the suspension members and the rail-base, substantially as described.

GERMAN L. BAXTER.
